US00D785153S

(12) **United States Design Patent** (10) **Patent No.:** **US D785,153 S**
(45) **Date of Patent:** **** Apr. 25, 2017**

(54) **AIR FILTRATION DEVICE**

(71) Applicant: **Illinois Tool Works Inc.**, Glenview, IL (US)

(72) Inventors: **Stephen J. McPhiliamy**, Chicago, IL (US); **Antonio J. Belton**, Richton Park, IL (US); **John S. White, Jr.**, Chicago, IL (US); **Ryan L. Francis**, Palatine, IL (US)

(73) Assignee: **Illinois Tool Works Inc.**, Glenview, IL (US)

(**) Term: **15 Years**

(21) Appl. No.: **29/560,847**

(22) Filed: **Apr. 11, 2016**

Related U.S. Application Data

(62) Division of application No. 29/484,485, filed on Mar. 10, 2014, now Pat. No. Des. 758,558.

(51) **LOC (10) Cl.** **23-04**

(52) **U.S. Cl.**

USPC **D23/364**

(57) **CLAIM**

The ornamental design for an air filtration device, as shown and described.

DESCRIPTION

FIG. 1 is a top front right perspective view of an air filtration device of our new design.

FIG. 2 is a top back right perspective view thereof.

FIG. 3 is a front side elevational view thereof.

FIG. 4 is a back side elevational view thereof.

FIG. 5 is a right side elevational view thereof.

FIG. 6 is a top plan view thereof; and,

FIG. 7 is a bottom plan view thereof.

The broken lines showing parts of the drawings are included to illustrate use and environment and form no part of the claimed design.

1 Claim, 7 Drawing Sheets

US D785,153 S
